UNITED STATES PATENT OFFICE.

MAURICE H. ROBERTS, OF BOSTON, MASSACHUSETTS.

CULINARY BEATER.

1,289,545.

Specification of Letters Patent. Patented Dec. 31, 1918.

Application filed July 18, 1917. Serial No. 181,399.

To all whom it may concern:

Be it known that I, MAURICE H. ROBERTS, a citizen of the United States, and a resident of Roxbury district, of the city of Boston, 5 the county of Suffolk, State of Massachusetts, have invented an Improvement in Culinary Beaters, of which the following description, in connection with the accompanying drawing, is a specification, like 10 characters on the drawing representing like parts.

This invention relates to culinary beaters and mixers and the like, more particularly it relates to hand operated beaters for beating 15 eggs, frosting, confectioneries and the like. In order to illustrate my invention I have shown in the accompanying drawing one embodiment thereof; wherein; Figure 1, is an elevation of a beater embodying my in- 20 vention.

Fig. 2, is a horizontal section on line 2—2 of Fig. 1.

Fig. 3, is a horizontal section on line 3—3 of Fig. 1.

25 And Fig. 4, is a modification hereinafter described.

The terms employed herein are used in the generic and descriptive sense and therefore are not intended primarily as terms of limitation.

30 In the drawing 20 represents a base of any suitable or preferred type or form best adapted for a contact member to engage the interior bottom of any desired vessel or container utilized to hold the article to be mixed or beaten.

35 Pivots 21 and 22 are located at diametrically opposite positions upon the said base 20 and swiveled thereon are the beater members 23 and 24 respectively.

The said beater members 23 and 24 are preferably circular or circumferential in form both of the same size or of the same diameter and with their axes at all times in 45 a plane transverse one to the other whether in rotation or stationary by the means provided hereinafter. Integral or secured to said beater members in any suitable manner at the top thereof are relatively thin, flat, 50 spiral or twisted members 27 and 28 respectively each adapted to extend flatwise through the slots 29 and 30 through the reciprocating bar 32 secured to or integral with the reciprocating rod 33 at right angles thereto.

55 The upper ends of said members 27 and 28

are pivoted or rotatable at 35 and 36 respectively in holes in the guide bar or brace 38 which has a centrally located slot 39 through which the reciprocating rod 33 is 60 vertically slidable. Therefore, while the reciprocating bar 32 is slidable axially of the members 27 and 28 the bar or brace 38 is stationary thereto but allows of pivotal movement of the said members 27 and 28. 65 The reciprocating rod 33 is provided at the top thereof with a suitable handle 41 and interposed between which and the bar or brace 38 is a long spiral spring 42 encircling the said reciprocating rod. Interposed between 70 the bars 32 and 38 is a similar but shorter spiral spring or buffer spring 43 normally adapted to limit the upward movement of the handle 41 and the reciprocating rod 33 under the action of the spring 42. 75

Other suitable means than the bar 32 may be employed slidable longitudinally upon the members 27 and 28 to rotate them. For example, referring to Fig. 4, I illustrate a handle or grip 48 provided with a couple of 80 channels or counterbores each provided with a spring 50 to engage the stationary washers swiveled on the ends of the members 27 and 28 normally to force them out of said counterbore. Suitable slotted ferrules or the 85 like are provided to embrace the said members 27 and 28 to cause them to rotate in the same manner as does the bar 32.

The application and operation of my invention is as follows:

The article or substance to be mixed or beaten is placed as usual in the aforesaid container or vessel. The operator then grasps either the handle 41 or the handle 48 as the case may be and brings the base 20 90 into contact with the interior bottom in the said vessel. Then by a rapid down movement of the handle 41 the reciprocating rod 33 is moved downward carrying with it the reciprocating bar 32 causing the said members 27 and 28 to move through the slots 29 and 30 and as the said members 27 and 28 are spiral or twisted they will rotate. The direction of the spiral of the member 27 is 95 opposite that of member 28 so that the beater portions 23 and 24 will rotate in opposite directions during the said downward movement of the bar 32. Thus the beater 23 is adapted normally to pass within the circumferential or peripheral plane of the 100 beater 24 when the latter is entering and leaving the plane transverse to the former. 105 110

As continued rotation is had the relative positions of the said beaters 23 and 24 will change constantly but the axes thereof will always be transverse one to the other.

5 Eventually or during the next half revolution the beater 24 will pass within the circumferential or perpendicular plane of the beater 23. In this manner each beater will alternately pass the other beater as the axis of one or the other crosses the opposite one in the plane of rotation. When the extreme downward movement of the handle 41 is reached the operator will permit the spring 42 to return the said handle until the buffer 10 spring 43 engages with the bar or brace 38 after which the aforesaid reciprocating portions will come to rest and the beaters 23 and 24 will then cease to rotate. During the said upward movement both beaters will 15 be rotated in a direction opposite to that which they rotated during the downward movement of the said handle. Therefore, during a complete reciprocation each beater will rotate in its own direction for two or three turns dependent upon the 20 length and pitch of the spiral members 27 and 28 after which they will then reverse their direction each assuming a different direction of rotation to that previously had.

25 30 By placing the beaters 23 and 24 close together and providing each with a spiral in the reverse direction to rotate them in reverse directions the edges thereof will have to pass within the outlines of the opposite beater and also each rotate in the opposite direction, and quicker and more complete mixing or beating is obtained than with devices heretofore known.

35 40 The construction of the beater is relatively simple and every part is open to inspection and cleansing. With regard to the modification illustrated by Fig. 4, the operation thereof is similar to that shown by Fig.

45 1. That is the rapid reciprocation of the member 48 which causes the beaters 23 and 24 to rotate in the same manner until the handle comes to rest, after which the springs 50 will return the said handle to its original position again causing said beaters to rotate 50 but in the reverse direction.

I have described herein one embodiment of my invention, but it is to be understood that the latter is not essentially limited to the specific details of construction and organiza-

tion of said embodiment, since the same may 55 be varied without departing from the proper scope of the claims.

Claims:

1. In an article of the character described, a plurality of beater members each pivoted 60 adjacent to the other upon a stationary base with their planes of rotation intersecting and provided with oppositely directed spiral portions, and a reciprocatory handle guiding means coöperating with said spirals to 65 rotate said members in opposite directions.

2. In an article of the character described, a plurality of beater members each pivoted adjacent to the other upon a stationary base 70 with their planes of rotation intersecting and provided with oppositely directed spiral portions, a reciprocatory handle guiding means coöperating with said spirals to rotate said members in opposite directions, and resilient means adapted to restore said handle into 75 the normal position to reverse the rotation of said members.

3. In an article of the character described, a plurality of beater members each pivoted 80 adjacent to the other upon a stationary base with their planes of rotation intersecting and provided with oppositely directed spiral portions extending therefrom and pivoted for rotation in a guiding brace, a brace including pivotal portions for the said spirals 85 and adapted to guide a handle means, a reciprocatory handle means passing through said brace and having on the end thereof means engaging said spiral portions to rotate the same in opposite directions, and resilient means to restore said handle to the 90 normal position and to reverse the rotation of said spiral portions.

4. In an article of the character described, a plurality of beater members each pivoted 95 adjacent to the other upon a stationary base with their planes of rotation intersecting and each provided with oppositely twisted spiral portions extending therefrom to cooperate with pivotal and bracing means at a 100 distance from said members, pivotal bracing means for said spiral portions and reciprocating means engaging said spiral portions between the point of pivotal and bracing means for actuating said spiral portions.

In testimony whereof, I have signed my name to this specification.

MAURICE H. ROBERTS.
